LIQUID FUEL BURNER

Raymond F. Blake, Newburyport, Mass.

Application October 9, 1933, Serial No. 692,773

1 Claim. (Cl. 158—53)

This invention relates to fuel oil burners of the type in which the oil is usually pre-heated and delivered under pressure into a carbureting chamber in a fine jet or spray and which are primarily intended to be employed in stoves or ranges.

In certain oil burners of this type the pre-heating and spraying means comprise a horizontally disposed tube which is somewhat loosely insertable through an aperture in the carbureting chamber into which the nozzle at the end of the tube projects. An objection to this type of burner has been due to the fact that unconsumed oil is liable to run back from the nozzle on the surface of the tube, and to drip into the bottom of the chamber in which the burner is located, or elsewhere, this being particularly likely to occur at the time of starting the burner, or before it becomes thoroughly heated. Also, at such times, unconsumed oil is liable to accumulate within the burner and cause smoking and other objectionable results.

The objects of my invention are to provide an improved construction of burner of the type above referred to, in which means are provided for preventing back flow of liquid fuel on the outer surface of the jet nozzle and for catching the unconsumed liquid which may be discharged therefrom and also for collecting unconsumed fuel in the burner casing, so that it may be delivered to a suitable receptacle.

I accomplish these objects by means of the construction hereinafter described and illustrated in the accompanying drawing, in which the figure is a sectional view of a burner of the type referred to illustrating an embodiment of my invention.

The type of burner shown comprises a series of tubes 10 which are supported horizontally at each end in hollow castings 11 and are provided with burner apertures 12 at suitable intervals. A carbureting chamber 14 is mounted between the tubes 10 and is supported by an intake tube 15, which is mounted in one of the end castings 11 and opens into the chamber 14 opposite the discharge end of a supply, or generator tube 16, which is extended horizontally through an aperture in the wall of chamber 14 and has a small aperture 17 in its end through which the liquid fuel is discharged in a spray or jet, which is directed towards the middle of the entrance to tube 15. An air entrance passage 18 extends vertically downward from the bottom of the chamber 14, directly beneath the end of tube 16, so that air passing upward therein through its

open, lower end, will be mixed with the fuel delivered through the aperture 17 and the mixture will be discharged into the tube 15 and delivered to the adjacent end casting 11 and the burner tubes 10, in the normal operation of the burner.

According to my invention the end portion of the nozzle of the generator tube 16, which projects into the carbureting chamber, is provided with an annular groove 18' forming an annular lip, or flange 16'' at its end, which projects vertically therefrom.

While nearly all of the liquid fuel which is discharged from the nozzle aperture 17 will be delivered into the tube 15, a small portion, particularly before the tube 16 becomes thoroughly heated, is liable to flow down on the face of the nozzle, from which point it would tend to run back on the surface of the pipe 16 and pass outside the carbureting chamber, and then would drip therefrom at some objectionable point. This action is prevented by the lip 16'', from which the liquid will drip down through the air entrance passage 18. In this connection I further provide a drip cup 20 which is mounted in upright position on a nipple 21 directly beneath the entrance to the air passage 18, said nipple being supported by a pipe 22 which leads to any conveniently located receptacle, as 23, so that, when liquid drips from the lip 16'', through air passage 18, it will fall into the cup 20, from which point it may be conducted into the receptacle 23. Pipe 24 is arranged in open communication with the pipe 22 directly beneath the nipple 21, said pipe 24 being extended upward and connected to the bottom of the end casting 11, into which the vaporized fuel is initially discharged, so that unconsumed liquid therein may pass down said pipe 24 into the pipe 22, and thence into receptacle 23. A pipe 25 is mounted in the bottom of the cup 20 and in continuation with the nipple 21, and is extended upward into the air entrance passage 18, so that vapor which may be discharged from pipe 24 into pipe 22 may pass upward and be discharged into the air entering the passage 18, and may thereby be conducted again into the burner. An aperture 28 is formed in the pipe 25 adjacent the bottom of the cup 20, so that liquid which drips into the cup from the lip 16'' may drain into the pipe 22 and pass into the receptacle 23. The lower end of the nipple 21, which is located above the point where the pipe 24 enters the pipe 22, is preferably somewhat choked or reduced in diameter to provide a passage 30 which is of sufficient size to permit the liquid fuel which may drip into the cup

20 to pass into the receptacle 23, but which will prevent vapor from being drawn from the burner castings through pipe 24 and discharged from pipe 25 into the carbureting chamber in sufficient 5 quantity to vary substantially the mixture which is delivered to the burner through pipe 15.

With the above described construction all the liquid fuel which is discharged from the nozzle aperture 17 will eventually either be consumed or 10 will be conducted to the receptacle 23, and will not be permitted to drip into the bottom of the chamber containing the burner, or to cause smoking on account of partly consumed fuel.

I claim:

15 A liquid fuel burner comprising a casing having

a carbureting chamber provided with an air entrance passage in its bottom, a fuel nozzle extending into said chamber and having a depending drip flange adjacent the discharge end thereof arranged directly over said passage and in position to prevent back flow of the fuel on the surface of the nozzle, a receptacle arranged to receive liquid dripping from said flange, a drain pipe leading from said receptacle, a pipe connecting the bottom of said casing and said drain pipe, and a pipe connected to said drain pipe and opening into said air entrance passage, to return vaporized fuel thereto.
